DESIGN FOR A MOTOR DRIVEN TANK TRUCK

Robert E. Billings, City Island, N. Y., assignor to
Richfield Oil Corporation of New York, New
York County, N. Y.

Application May 29, 1934, Serial No. 51,956

Term of patent 7 years

To all whom it may concern:

Be it known that I, Robert E. Billings, a citizen of the United States, residing at No. 477 King Ave., City Island, New York, have invented a new, original, and ornamental Design for Motor Driven Tank Truck, of which the following is a specification, reference being had to the accompanying drawing, forming part thereof.

Figure 1 is a front perspective of the motor driven tank truck.

Figure 2 is a side view of the ornamental design.

The material parts of my design are shown in solid lines and the immaterial parts are shown in dotted lines.

I claim:

The ornamental design for a motor driven tank truck, substantially as shown and described.

ROBERT E. BILLINGS.
